Attorney

UNITED STATES PATENT OFFICE.

FRED CZECH, OF WICHITA FALLS, TEXAS.

INCANDESCENT ELECTRIC LAMP.

Application filed June 17, 1925. Serial No. 37,781.

This invention relates to improvements in electric lamps of the incandescent type and has for its principal object to provide a lamp wherein a pair of independent filaments is provided, so that when one of the filaments should burn out or accidentally become broken, the other filament will be adapted to function so as to enable the electric lamp to be further used until said last mentioned filament burns out or becomes broken.

Another important object of the invention is to provide an incandescent lamp of the above mentioned character wherein the same has its base provided with a pair of independent positive contacts which are adapted to cooperate with the socket provided for the base of the electric lamp, one of said contacts being rendered inoperative when the other contact is in use.

A still further object is to provide an incandescent lamp of the above mentioned character which is simple in construction, inexpensive, strong and durable, and further well adapted to the purpose for which it is designed.

Other objects and advantages of this invention will become apparent during the course of the following description taken in connection with the accompanying drawing.

In the accompanying drawing forming a part of this application and in which like numerals designate like parts throughout the same:

Figure 1 is a side elevation of the incandescent lamp embodying my invention, and

Figure 2 is an enlarged fragmentary sectional view showing the relation of the lead in wires with respect to the shell which surrounds the base.

In the drawing, wherein for the purpose of illustration is shown the preferred embodiment of my invention, the numeral 1 designates generally my improved incandescent lamp, the same comprising the base 2, the metallic shell 3 which encircles the same, and is provided with a means for securing the lamp in the well known type of socket. Embedded in the base and extended upwardly therefrom is the usual glass plug 4, and the bulb which enclosed the plug and the filaments is indicated at 5.

The positive terminal or contact 6 which is provided at the bottom of the base 2 has associated therewith the spring strip 7, the purpose of which will hereinafter be more

fully described. A main lead in wire 8 extends through the base, and through the glass plug, the lower end thereof being in engagement with the positive contact 6. 60 The upper end of the main lead in wire 8 diverges as illustrated at 9 and connected at one end to the outer free end of the diverging end 9 of the main lead in wire 8 is the primary filament 10. The other end of the 65 primary filament is connected to the outer free end of the diverging portion 11 of the lead in wire 12 which extends through the glass plug 4, and the side of the upper portion of the base 2 engages the negative contact or shell 3 as at 13. This lamp as above described is of the well known type of a single filament lamp, and when the filament burns out or accidentally becomes broken, the lamp is rendered useless and must necessarily be replaced with a new one. 75

In order to overcome the above disadvantages, I have provided an auxiliary filament in connection with the primary filament so that when the primary filament becomes 80 burnt out or broken, the lamp need not be thrown away but may be further used, thus saving considerable expense. The construction of the auxiliary filament and the supporting means therefor will be presently described. 85

Extending upwardly from the main lead in wire 8 at a point adjacent the juncture of the diverging portion 9 is the wire 14. An additional lead in wire 15 extends longitudinally through the glass plug 4, and the upper ends of the wires 14 and 15 are connected through the medium of the auxiliary filament 16. The lower end of the lead in wire 15 extends laterally through the plug 4, 95 and is connected to the contact 17 which extends outwardly of the metallic shell 3 adjacent the upper edge thereof and is insulated as at 18.

Under normal conditions, when the incandescent lamp is in its socket, the contact 17 does not engage the socket and the current will flow through the wires 8 and 12, and the primary filaments 10, whereby the lamps will be properly illuminated. When the 100 primary filament ceases to function, it is only necessary to further screw the shell 3 of the lamp into the socket provided therefor, so that the contact 17 will engage the metallic portion of socket, and thus enable 105 the current to flow through the wires 8 and 15, and through the auxiliary filament 16. 110

In this manner the auxiliary filament will render the lamp luminous.

It will thus be seen from the foregoing description, that a double filament incandescent lamp has been provided which will be very inexpensive in its manufacture, and furthermore at all times positive and efficient in carrying out the purposes for which the same is designed.

10 While I have shown the preferred embodiment of my invention, it is to be understood that minor changes in the size, shape and arrangement of parts may be resorted to without departing from the spirit of the invention and the scope of the appended claim.

Having thus described the invention, what I claim as new and desire to secure by Letters Patent is:

An incandescent lamp comprising a base, 20 a metallic shell surrounding the same, a glass plug carried by the base, a bulb enclosing the same, a terminal at the bottom of the base, a main lead in wire extending through the base and said plug and connected at its lower end to said terminal, a com-

plementary lead in wire extending through the plug, a lower end thereof being in engagement with said metallic shell, a primary filament bridging the upper end of said wires, a contact carried by the base and extending through the shell at a point adjacent the upper edge thereof, and being insulated therefrom, an additional lead in wire connected at its lower end with said contact and extending upwardly through the plug, a 35 branch wire extending upwardly from the main lead in wire, an auxiliary filament bridging the upper edge of the branch wire and the last mentioned lead in wire, and a spring strip carried by the base and being in 40 engagement with the terminal, the aforementioned contact being out of engagement with a lamp receiving socket when the primary filament is in use, said spring strip permitting the plug to be inserted in its 45 socket so as to bring the contact into engagement with the socket when the primary filament is rendered inoperative.

In testimony whereof I affix my signature.

FRED CZECH.
